UNITED STATES PATENT OFFICE

LEE W. SARGENT, OF RED WING, MINNESOTA, ASSIGNOR TO JOHN B. BRADY, OF WASHINGTON, DISTRICT OF COLUMBIA

VENDING MACHINE

Application filed July 27, 1925. Serial No. 46,327.

1. My invention relates broadly to vending machines and more particularly to a machine for delivering commodities such as milk, butter, cheese, bread and other food products and beverages, by the insertion of a coin in a slot to permit the withdrawal of the package to be delivered.

One of the objects of my invention is to provide a vending machine of simplified construction which may be readily manufactured 10 for installation in factories, schools, pleasure resorts and in various sections of residential districts of towns to deliver to customers food products upon the insertion of coins in slots provided therefor.

15. Another object of my invention is to provide a simplified construction of vending machine in which a revolving cylinder member is provided for the selection of the package which it is desired to deliver, which member may be actuated by an external crank arm only after the insertion in the machine of coins in the proper amount, with means for locking the machine against unauthorized tampering at all other times.

20. Still another object of my invention is to provide a construction of vending machine in which the working parts are disposed within a casing forming a support for the machine and the articles to be delivered carried in a display rack position substantially at 25° to the supporting base in order that the articles which are to be vended may be clearly visible to the customer.

25. I have described my invention with particular reference to a vending machine for bottles of milk, but it will be understood that other food products may be delivered by the machine and that no limitations as to the use of the machine are intended.

30. My invention will be more fully understood from the specification hereinafter following by reference to the accompanying drawings, in which:

35. Figure 1 is a front view of the vending machine; Fig. 2 is a vertical cross sectional view on line 2—2 of Fig. 1 through the machine; Fig. 3 is a cross sectional view on line 3—3 of Fig. 2 showing the operating parts in locked position; Fig. 4 is a cross sectional

view of the parts illustrated in Fig. 3 but showing a coin inserted in the slot for releasing the locking mechanism permitting the rotation of the delivering member for the delivery of a package; Fig. 5 is a cross sectional view of the parts illustrated in Fig. 4 showing the locked mechanism entirely removed 55 from the path of the revolvable member allowing complete rotation of the revolvable member for the delivery of the desired 60 article; Fig. 6 is a fragmentary cross sectional view through the machine taken on line 6—6 of Fig. 2; Fig. 7 is a cross sectional view taken on line 7—7 of Fig. 3; Fig. 8 shows a partial side elevation of the machine with 65 the casing broken away to clearly indicate the working parts therein; Fig. 9 is a perspective view of the revolvable cylindrical member; and Fig. 10 is a perspective view of one of the pairs of end guide plates which I 70 provide on the revolvable member.

Referring to the drawings in more detail, reference character 1 indicates a supporting casing for the vending machine. Reference character 2 shows the vertical display casing 75 which extends upwardly from the supporting base substantially at an angle of 25° from the supporting base which contains the bottles of milk or other articles of merchandise 80, which are arranged to slide vertically between partition members 3 and 4 visible through glass panel 5. The cabinet portion 2 terminates in a lower extension 7 of a size into which the bottle of milk 6 may be readily deposited and withdrawn by the customer 85 through the aperture provided therefor as represented in Figs. 1 and 2. A revolvable member 8 is journaled in the lower end of the display cabinet 2 at points 10 and 11, the journal 11 being supported in a bracket 12 90 so which is secured to the display cabinet 2. The revolvable member 8 has a pocket 9 therein of a shape and size sufficient to receive the article or package which is to be vended. In the construction illustrated the pocket 9 is of 95 a size to receive a bottle of milk 6 and deliver the same into pockets 7. The revolvable member 8 is actuated by a crank arm 14 extending from the front of the machine in a convenient position to be grasped by the cus- 100

tomer for driving the revolvable member in one direction only. The revolvable member 8 has a reduced portion 15 extending from one end thereof with a cam face and abutment 16 protruding therefrom. A ratchet 19 is carried adjacent the revolvable member 8 to cooperate with a pall 20 carried upon the frame of the supporting casing 1. A pair of end flanges 17 and 18 are provided on the reduced portion 15 each having an elongated 5 protrusion 17^a and 18^a at one side of the periphery thereof. A pivot member 21 is provided for journaling locking bars 22 and 23 in a position where the ends 22^b and 23^b extend within the inturned edges of the 10 flange members 17 and 18 while the ends 22^a and 23^a extend beneath the coin slots 24 and 25. The locking bars 22 and 23 are normally balanced in such manner that ends 22^b and 23^b 15 gravitate toward the reduced portion 15 of revolvable member 8 with the ends thereof in abutment with the ends 22^b and 23^b of the locking bars 22 and 23. By reason of the 20 pall and ratchet mechanism 19 and 20 the 25 rotation of the revolvable member 8 can only take place in counterclockwise direction, such rotation being normally prevented by the abutment of the locking bars against the 30 protrusion 16. In Fig. 3 the machine is illustrated in locked position with the coin 26 about to slide down the slot 24. In Fig. 4 the coin is shown in position 26^a in engagement with the ends 22^a of the locking bar 22 35 raising the end 22^b of the locking bar 22 free of engagement of the protrusion 16. In Fig. 5 the coin is illustrated in position 26^b still further raising the locking bar 22 free of engagement with the abutment 16 on the 40 revolvable member enabling the revolvable member to freely turn in its journal, for delivering one bottle of milk 6. I provide two coin slots 24 and 25 for coins of different denominations to make up the sum required for the purpose of purchasing the article to 45 be vended. The movement of the locking bars 22 and 23 is oscillatory and in order to prevent tampering with the machine by locking the entire machine through different angles in the attempt to gravitate the bars 22 50 and 23 out of position, I may provide any form of safety device positioned upon pivots beneath the locking bars 22 and 23 to be brought into position when the machine is rocked into a different plane. The employment 55 of this form of safety device prevents the operation of the machine when the machine is tipped.

It will be observed that the operation of the machine is positive and the construction 60 and operation of parts extremely simple. The construction illustrated has been practically employed and operated giving extremely satisfactory service. It will be observed that packages of cubical or rectangular contour 65 may be employed without departing from the

spirit of my invention. I desire that it be understood that further modifications may be made and that I intend no limitations upon the invention other than those imposed thereon by the scope of the appended claims.

What I claim and desire to secure by Letters Patent of the United States is as follows:

1. A coin controlled mechanism for vending machines comprising in combination a rotatable delivery device, a longitudinally extending abutment on said device, a plurality of guidemembers carried by said rotatable delivery device, a plurality of locking levers arranged to normally engage said abutment and obstruct the rotation of said device, and a plurality of coin chutes for receiving coins and directing the same against the extremities of said locking levers for moving said locking levers to a position free from said abutment and free of obstructing the rotation of said device, whereby said rotatable delivery device may be moved to a selected position and said locking levers controlled by the movement of said guide members.

2. A coin controlled mechanism for vending machines comprising in combination a rotatable delivery device, a longitudinally extending abutment, a pair of locking levers, for normally engaging said abutment and obstructing the rotation of said rotatable delivery device, an independent guide for each lever, a plurality of coin delivery chutes arranged over each of said means for receiving coins of different denominations and directing said coins against said levers and by their conjoint action raising said levers to a position out of the path of said abutment and rotatable delivery device for permitting said rotatable delivery device to be moved to a selected position, said guides limiting the movement of each of said levers when coins are inserted in said chutes.

3. A coin controlled mechanism for vending machines comprising a rotatable delivery device, a cylindrical extension on said device, a longitudinally extending abutment on said extension, a plate member at each end of said extension having inturned flanges directed toward each other and having a contour conforming with the periphery of said cylindrical extension and said abutment, a pair of locking levers pivotally mounted intermediate their end at points adjacent said rotatable delivery device, a coin chute projecting over the outer ends of each of said levers, the inner ends thereof extending beneath said inturned flanges and normally engaging said longitudinally extending abutment, said levers being arranged to be elevated out of engagement with said abutment by the weight of coins deposited in said chutes and limited in the movement thereof by said inturned flanges for effecting rotation of said device and delivering an article therefrom.

4. A coin controlled mechanism for vend-

ing machines comprising a rotatable article delivery member, an extension on one end of said rotatable member, an abutment formed on said extension, a pair of locking bars each pivotally mounted adjacent said article delivery member and having their ends normally extended in engagement with said abutment for preventing movement of said rotatable member, a pair of continuous guides for controlling the movement of said bars and a pair of coin chutes positioned over opposite ends of said locking bars, whereby coins deposited in said coin chutes may be utilized for removing the ends of said locking bars from the path of rotation of said abutment for delivering one of the articles from said rotatable article delivery member.

5. A coin controlled mechanism for vending machines comprising a rotatable article delivery member, an extension on one end of said rotatable member, an abutment formed on said extension, a pair of locking bars, a pair of inturned flanges positioned at spaced intervals upon said extension and forming guides for the ends of said pair of locking bars, said locking bars being pivotally mounted adjacent said rotatable article delivery member, with their opposite ends extending to a pair of coin chutes, whereby the ends of said locking bars may be moved out of engagement with said abutment by depositing coins in said coin chutes for permitting rotation of said rotatable article delivery member for effecting the delivery of an article from said rotatable article delivery member.

35 In testimony whereof I affix my signature.
LEE W. SARGENT.
